UNITED STATES PATENT OFFICE.

THOMAS E. KELLEHER, OF BATAVIA, ILLINOIS, ASSIGNOR TO T. W. SNOW CONSTRUCTION COMPANY, OF CHICAGO, ILLINOIS, A CORPORATION OF ILLINOIS.

STAND-PIPE.

1,280,757.

Specification of Letters Patent.

Patented Oct. 8, 1918.

Application filed March 15, 1918. Serial No. 222,533.

To all whom it may concern:

Be it known that I, THOMAS E. KELLEHER, a citizen of the United States, residing at Batavia, in the county of Kane and State 5 of Illinois, have invented a new and useful Improvement in Stand-Pipes, of which the following is a specification.

My invention relates, more particularly, to stand pipes which are provided as portions of railway equipment, alongside of 10 the tracks to furnish water to the tenders of locomotives.

The conditions as regards railway rolling stock and the operation of the same, are 15 such, according to present-day practices, that the stand pipes must be made of such height in order to adapt them to fill the water compartments of locomotive tenders, and avoid obstruction to the rolling stock, 20 that the water valve-operating mechanism provided on the stand pipe usually on a relatively rigid part thereof above the nozzle of the pipe, is located at such a height as to be very inaccessible to the operator on the 25 tender, especially when the tender is a relatively low one, this condition not only making it difficult for the operator to actuate the water valve, but rendering the operation thereof oftentimes hazardous.

My primary object is to provide a construction of stand pipe wherein the water-valve operating mechanism, even when a 30 relatively high stand pipe is used, is readily accessible for operation by the operator 35 while occupying a comparatively safe place on the tender, to the end of reducing danger to the operator and making his work easier.

Referring to the accompanying drawing, Figure 1 is a view in side elevation of the 40 upper end of a stand pipe embodying my improvements. Fig. 2 is a plan view of the outer end of the stand pipe; and Fig. 3, a broken perspective view of the overhead frame of the stand pipe and a portion of the 45 valve-operating mechanism shown in Fig. 1.

I have chosen to illustrate my invention in connection with a certain construction of stand pipe of a particular type, but without any idea of limiting the use of the invention 50 thereby. In the particular construction shown, the stand pipe is formed of the hollow riser or standard 4, which, in practice, connects with the supply of water which is to be delivered through the stand pipe and 55 into the tenders, communication of the pipe

4 with the water supply being controlled by means of a valve, not shown, but which is common practice. The upper end of the upright 4 terminates in a laterally-extending portion 5, which is telescoped with a spout 60 section 6, this spout loosely fitting over the extension 5. The spout is provided at opposite sides at its rear end with rollers 7, one only of which is shown, journaled thereon, which travel in curved guide-ways 8 provided at opposite sides of the spout 6, these 65 guide-ways being rigidly secured to a framework 9, which is connected at one end with a bracket 10 securely fastened to the upper end of the upright 4. The guides 8, which 70 are provided in the same relative position at opposite sides of the spout 6, in combination with the rollers 7, serve as a means for permitting the spout to be drawn out relative to the extension 5 and tilted downwardly 75 at its forward, discharge, end. Coöperating with the guide-ways 8 and rollers 7, is a flexible element 10, such as a chain, which is connected at its forward end with the forward portion of the spout 6, as indicated at 80 11, extends over pulleys 12 and 13 on the frame 9 and at its opposite end is counter-weighted in a manner not shown, but in accordance with common practice, this feature 85 of the construction permitting the spout to be raised and lowered at will and retained in the position to which it is moved.

My invention relates particularly to the feature of actuating the valve which controls the flow of water into the upright 4, and in 90 accordance with the preferred embodiment illustrated, the valve hereinbefore referred to, but not shown, is so operatively connected with the vertically movable bar 13 as to cause the valve to be opened when the rod 95 13 is raised, and closed when this rod is lowered. This rod is pivotally connected as indicated at 14 with one arm of a bell-crank 15 pivoted at 16 to the upright 4, the upper 100 end of this bell-crank being pivotally connected at 17 with a rod 18, which extends generally lengthwise of the frame 9. In practice, it is preferred that the parts just described and including the rods 13 and 18 and bell crank 15, be provided at opposite 105 sides of the stand pipe structure. The forward ends of the rods 18 are pivotally connected at the pins 23, with the arms 21 of a yoke 22, the arms of which straddle the forward end of the frame 9 and are pivoted 110

thereto on the pivot pins 20, one only of which is shown, but which are provided at opposite sides of the frame 9 to extend outwardly therefrom in a lateral direction and beyond the outer faces of the arms 21, these pins being preferably of reduced diameter at their outer ends at which reduced portions they engage the bars 18. The valve-operating structure is provided with two handles, one represented at 24 and forming a part of the yoke-member 22 and extending medially thereof in an upward and rearward direction in the closed position of the valve, as shown in Fig. 1, and the other represented at 25 and extending substantially horizontally and forwardly into a position wherein it may be easily grasped by the operator on the tender, in the closed position of the valve. The handle 25 is shown as formed separately from the yoke 22, but rigidly connected therewith at its portion 26 through the medium of rivets 27, the shape of this lever, by preference, being such, as shown, as to cause it to extend at its under surface in contact with the enlarged portion of the adjacent pivot pin 23, in the normal position of the apparatus, the forward end of the handle 25 being preferably laterally offset as represented, it being understood from the foregoing that the handle 25 extends laterally beyond the spout 6, as shown in Fig. 2, thus permitting this handle to be thrown down alongside the spout without obstruction.

In the use of the device to open the water valve, the operator standing on the tender, grasps the lever 25 and by pulling downwardly on the latter, rotates the yoke 22 on the pivots 20 in counterclockwise direction in Fig. 1, thus shifting the rods 18 forwardly, rocking the bell-cranks 15 in anti-clockwise direction in Fig. 1 and raising the rods 13. In this movement of the member 22, the handle 24 is swung forwardly to a position in which it may be readily grasped by the operator to further move the valve in the same direction, should the handle 25, before the desired position of the valve is reached, have moved out of accessible position to the operator, or should operation by the lever 24 be more convenient.

The pivots 23 are preferably so disposed relative to the pivots 17 and 20 that they will extend slightly below the planes in which the pivots 17 and 20 extend, when the valve is in closed position. Thus, the tendency of the parts of the valve-operating mechanism will be to remain in the position shown in Fig. 1 and danger of accidental opening of the valve is greatly minimized.

While I have illustrated and described a particular construction embodying my invention, I do not wish to be understood as intending to limit it thereto, as the same may be variously modified and altered with-

out departing from the spirit of my invention, it being my intention to claim my invention as fully and completely as the prior state of the art will permit.

What I claim as new and desire to secure by Letters Patent is—

1. In a stand pipe, the combination of an upwardly-extending conduit having an extension projecting laterally therefrom and movable up and down at its discharge end, and valve-operating mechanism including hand-operated elements through the medium of which said mechanism is actuated, one of said elements being supported to extend laterally beyond said extension to adapt said last-referred-to element to move up and down alongside said extension, the whole being constructed and arranged to cause the other of said hand-operated elements to be moved into a position for continuing the operation of said mechanism when the latter is moved out of its initial position.

2. In a stand pipe, the combination of an upwardly-extending conduit having an extension projecting laterally therefrom and movable up and down at its discharge end, and valve-operating mechanism including hand-operated levers extending in different directions and through the medium of which said mechanism is actuated, one of said levers being supported to extend laterally beyond said extension to adapt said last-named lever to move up and down alongside said extension, the other of said levers being brought into a position for continuing the actuation of said mechanism when the latter is moved out of its initial position.

3. In a stand pipe, the combination of an upwardly-extending conduit having an extension projecting laterally therefrom and movable up and down at its discharge end, and valve-operating mechanism including hand-operated levers, one of which extends forwardly and the other rearwardly in the normal position of said mechanism, said forwardly-extending lever being supported to extend laterally beyond said extension to adapt this lever to move up and down alongside said extension, and said rearwardly-extending lever being so positioned as to cause it to move into a position wherein it serves as the medium through which said mechanism is operated upon actuating said forwardly-extending lever.

4. In a stand pipe, the combination of an upwardly-extending conduit having an extension projecting laterally therefrom and movable up and down at its discharge end, and valve-operating mechanism including a yoke-member pivoted to extend above said extension, and a forwardly-extending lever and a rearwardly-extending lever connected with said yoke-member and through the medium of which the latter is actuated, said forwardly-extending lever extending later-

ally beyond said extension to adapt said forwardly-extending lever to move up and down alongside said extension.

5. In a stand pipe, the combination of an upwardly-extending conduit having an extension projecting laterally therefrom and movable up and down at its discharge end, a member connected with said conduit extending lengthwise of said extension, and 10 valve-operating mechanism including a yoke-member pivoted at its arms to said first-named member and extending above said extension, said yoke-member having a rearwardly-extending handle-section, and a 15 forwardly-extending lever connected with said yoke-member, said lever extending laterally beyond said extension to adapt said

lever to move up and down alongside said extension.

6. In a stand pipe, the combination of an 20 upwardly-extending conduit having an extension projecting laterally therefrom and movable up and down at its discharge end, and valve-operating mechanism including a rock-member having a handle-section ex- 25 tending rearwardly and carrying a pivot pin, and a lever connected with said rock-member in the rear of its pivot pin, and bearing intermediate its ends on said pivot pin, said lever extending forwardly and ex- 30 tending laterally beyond said extension to adapt said lever to move up and down alongside the latter.

THOMAS E. KELLEHER.
